UNITED STATES PATENT OFFICE.

BURT V. FLANNERY, OF PHILADELPHIA, PENNSYLVANIA, ASSIGNOR TO CANNON MANUFACTURING COMPANY, OF KANNAPOLIS, NORTH CAROLINA, A CORPORATION OF NORTH CAROLINA.

DESIGN FOR A TOWEL OR THE LIKE.

Application filed November 3, 1926. Serial No. 19,579. Term of patent 3½ years.

To all whom it may concern:

Be it known that I, BURT V. FLANNERY, a citizen of the United States, residing in Philadelphia, Pennsylvania, have invented a new, original, and ornamental Design for a Towel or the like, of which the following is a specification, reference being had to the accompanying drawing, in which the figure is a view of a towel or the like, embodying my new design.

I claim:

The ornamental design for a towel or the like, substantially as shown.

BURT V. FLANNERY.
